UNITED STATES PATENT OFFICE.

IVAN W. JAMIESON, OF PALMS, CALIFORNIA.

LATHING STRIP.

Application filed February 5, 1924. Serial No. 690,844.

To all whom it may concern:

Be it known that I, IVAN W. JAMIESON, a citizen of the United States, residing at Palms, in the county of Los Angeles and 5 State of California, have invented new and useful Improvements in Lathing Strips, of which the following is a specification.

This invention relates to a lathing strip, the general object of the invention being to 10 form a strip formed of a plurality of laths and a backing of felt, paper or the like which prevents moisture from reaching the lath.

Another object of the invention is to provide improved means for fastening the laths 15 together and to the backing.

This invention also consists in certain other features of construction and in the combination and arrangement of the several parts, to be hereinafter fully described, 20 illustrated in the accompanying drawings and specifically pointed out in the appended claims.

In describing my invention in detail, reference will be had to the accompanying 25 drawings wherein like characters denote like or corresponding parts throughout the several views, and in which:—

Figure 1 is a face view of a lathing strip constructed in accordance with this invention.

Figure 2 is a section on line 2—2 of Figure 1.

Figure 3 is a similar view showing how the parts are assembled together.

Figures 4 and 5 are views showing how the lathing strip is used.

Figure 6 is a view showing how the laths are cut to provide the beveled edges.

As shown in these views, the strip is 40 formed of a plurality of laths 1 and a sheet 2 of felt or the like to which the laths are secured by means of the strips of wire 3 which are provided with the kinks 4 which are pressed into the laths. As shown, these wires are used for holding the laths together 45 by running the lengths of wires transversely of the laths and pressing the kinks into the front faces of the laths and they are also used for fastening the backing sheet to the

laths by pressing the kinks in the lengths of 50 wires in rear of the strip through the backing sheet into the laths. These wires not only serve as connecting means but also act as reinforcements for the strip. The laths are each provided with a beveled edge 5 so 55 that the bond or key 6 of the mortar A will be firmly held between the laths. This bevel can be formed by tilting the laths, as shown at B in Figure 6, and cutting them on the line C so that each lath is split in 60 half and each half has a beveled edge. The strip can be applied directly to the studding, as shown in Figures 4 and 5 and it should be applied so as to break joints. The article is 65 mainly designed for exterior work with cement or stucco. The felt backing has a tendency to prevent moisture reaching the wooden lath or stucco and the strip can be manufactured on a conveying belt so that the product can be turned out very quickly and 70 cheaply.

It is thought from the foregoing description that the advantages and novel features of my invention will be readily apparent.

I desire it to be understood that I may 75 make changes in the construction and in the combination and arrangement of the several parts, provided that such changes fall within the scope of the appended claims.

What I claim is:—

1. A strip of the class described comprising a backing sheet, a plurality of laths placed thereon and spaced apart, wires on the front and rear faces of the strip and having portions pressed into the laths to 85 hold the laths together and to hold the backing sheet in place.

2. A strip of the class described comprising a backing sheet, a plurality of laths placed thereon and spaced apart, wires on 90 the front and rear faces of the strip and having portions pressed into the laths to hold the laths together and to hold the backing sheet in place, each lath having a beveled edge.

In testimony whereof I affix my signature.

IVAN W. JAMIESON.
